UNITED STATES PATENT OFFICE

ALFRED UNGELENK AND WALTER HOFMANN, OF THURINGIA, GERMANY, ASSIGNEES
TO GENERAL ELECTRIC COMPANY, A CORPORATION OF NEW YORK

DEVICE FOR SUPPORTING METAL PARTS WITHIN A VACUUM TUBE

Application filed April 11, 1930, Serial No. 443,587, and in Germany April 20, 1929.

In order to position an electrode or other metal part within a vacuum tube, it is usual to support the member by means of metallic wires, bars, tubes or the like which are sealed 5 in glass. However, if the supports project beyond the electrode, it has been found that an unfavorable distribution of electric field exists within the glass with attendant stress which may give rise to rupture, particularly 10 in the event that adjacent seals are close together. The problem of preventing these deleterious stresses occurs more frequently in the design of cylindrical members which surround the discharge space of a glow cathode tube.

An object of the present invention is to provide an improved structure for supporting electrodes within the interior of an envelope, the arrangement being such as to obviate the difficulties stated. Other objects 20 and features will be apparent as the specification is perused in connection with the accompanying drawing, in which Fig. 1 is a longitudinal view partly in section and partly diagrammatic of an X-ray tube provided with an electrode support and improved in accordance with our invention, while Fig. 2 is a view partly broken away of a modified structure.

In Fig. 1, numeral 1 designates the envelope of an X-ray tube terminating at each end in a reentrant stem 2, 3. To the stem 2 there may be secured in the well known manner a combined anode and target 4, while the 35 stem 3 supports a cathode of any suitable and well known design, the electrodes being arranged in endwise opposed relation as shown. The envelope is contained in a protective covering of suitable insulation material such as a phenolic condensation product or porcelain made in two parts 6, which are clamped at their inner edges within a metal cylinder 7. The latter is provided with a suitable window 8 from which the X-rays emerge. Between the electrodes 4, 5 and the envelope, there is supported in the improved manner described hereinafter a metal cylinder 9 which surrounds the discharge zone in order to protect the envelope from the effects 50 of the discharge. This cylinder is also pro-

vided with an aperture 10 which registers with window 8 in the outer metal cylinder. For spacing the member 9 from the envelope, we propose to utilize a plurality of wires 11, preferably stiff, which may be spaced 55 equi-distantly about the envelope and fused thereto at positions which do not extend appreciably beyond the said member. In Fig. 1 these positions are exemplified as being substantially in line with the longitudinal edges 60 of the cylinder 9 and contained wholly within the confines of the latter. The wires 11 are given a direction toward the cylinder which is partly radial and partly longitudinal, i. e. diagonally with respect to the principal axis of the tube and may be welded to the cylinder or secured thereto in any other suitable manner. In practice, the wires 11 are secured to the cylinder preferably before being fused to the envelope. It is evident 70 that if three such wires are provided and welded to each end of the cylinder, spaced substantially 120° apart, the tripodal arrangement rigidly centers the cylinder within the envelope and facilitates the fusing of 75 the wire to the glass. Moreover, it is also apparent that this supporting arrangement offers considerable advantage in protecting the envelope from fracture in the event the tube is jarred or subjected to sudden shock. Under these conditions, the tendency of the cylinder 9 to move relative to the envelope is counteracted by a compressional stress in one set of wires and a tensional stress in the other set which resolve themselves as forces along 80 the length of each wire due to the diagonal disposition of the latter. These wires preferably should be of sufficient gage and stiffness to withstand the stresses without deformation.

In Fig. 2, the wires 13 which position the cylinder 9 within the envelope, have directions normal to those shown in Fig. 1 and extend inwardly toward the envelope. The positions at which the wires are fused to the 95 glass are thus farther removed from the edge of the cylinder and are less endangered by electrical stresses. In this modification, it may be desirable to attach the wires 13 to the cylinder 9 substantially at the outer edges of 100

the latter, as shown. In the case of jar or other sharp movement given to the envelope, the resulting mechanical stresses are communicated to the wires as forces acting along 5 their axes, as was explained in connection with Fig. 1. While we have shown and described the wires 11 and 13 as taking the form of stiff members, it is apparent that, if desired, these wires may include one or more 10 loops or bends in order to offer any desired degree of resiliency. However, in the ordinary technique of tube construction, it is found more practical to require a strictly rigid 15 position of the cylinder 9 within the envelope such as would be accorded by the stiff wires.

It is also evident that while the arrangement of three wires at each end of the cylinder is advantageous in presenting a rigid 20 support and in which the wires divide equally the mechanical forces attending any movement of the cylinder 9, it may be desirable under the circumstances of unusual weight or size of the part to be supported, to employ 25 more than three wires. It is found that when the metal members within the tube are supported in the improved manner, the envelope is not subject to those failures which may be attributed to the specific supporting 30 structures heretofore employed. Our invention also has the distinct advantage of requiring the minimum amount of change in the configurations of the prior art tubes and of the metal members contained therein.

35 What we claim as new and desire to secure by Letters Patent of the United States, is:

1. The combination of a cylindrical envelope containing a plurality of cooperating electrodes in endwise opposed relation, a cylindrical metal member surrounding the discharge space between the electrodes and concentrically mounted within the envelope, means for supporting said member, said 40 means comprising a plurality of wires equidistantly spaced about the periphery at both ends of said member, said wires extending radially from the member and secured to the peripheral surface of the envelope at positions contained wholly within the length of 45 said member.

2. The combination of a cylindrical envelope containing a plurality of cooperating electrodes in endwise opposed relation, a cylindrical metal member surrounding the discharge space between the electrodes and concentrically mounted within the envelope, means for supporting said member, said 50 means comprising a plurality of wires equidistantly spaced about the periphery at both ends of said member, said wires extending from said member in diagonal directions with respect to the principal axis of the envelope, 55 and secured to the peripheral surface of the

envelope at positions contained wholly within the length of said member.

In witness whereof, we have hereto set our hands this 31st day of March, 1930.

ALFRED UNGELENK.
WALTER HOFMANN.
